DESIGN FOR A LAMP BASE.

Application filed July 28, 1926. Serial No. 18,525. Term of patent 3½ years.

To all whom it may concern:

Be it known that I, THOMAS JEFFERSON LEAGUE, a citizen of the United States, and resident of Chicago, in the county of Cook and State of Illinois, have invented a new, original, and ornamental Design for Lamp Base (Case 1), of which the following is a specification, reference being had to the accompanying drawing, forming part thereof.

Fig. 1, is a plan view of my novel design of lamp base, the view showing the complete

outline, though only a portion or a segment of the ornamentation appears thereon, it should be understood, however, that the balance of the unornamented portion within the outline involves a mere repetition of that portion more fully illustrated; and

Fig. 2, is a side elevation of the base.
I claim:

The ornamental design for a lamp base, as shown.

THOMAS JEFFERSON LEAGUE.
